UNITED STATES PATENT OFFICE.

WILLIAM KNAPP, OF CINCINNATI, OHIO.

FIFTH-WHEEL.

1,182,572.

Specification of Letters Patent.

Patented May 9, 1916.

Application filed March 30, 1911. Serial No. 617,871.

To all whom it may concern:

Be it known that I, WILLIAM KNAPP, a citizen of the United States of America, and a resident of Cincinnati, in the county of 5 Hamilton and State of Ohio, have invented a certain new and useful Improvement in Fifth-Wheels, of which the following is a specification.

This invention relates to improvements in 10 fifth-wheels, and its object is to simplify such a structure without sacrificing strength or durability and, also, to relatively decrease the cost of manufacture, to decrease its weight, to reduce the number of parts and to 15 render more effective its operation, and still further, to facilitate assembling and repairs.

The invention consists in certain novel 20 features of construction, together with the combination and arrangement of parts, such as will be hereinafter fully referred to and particularly pointed out in the claims.

In the accompanying sheet of drawings, Figure 1 is a fragmentary longitudinal elevation showing the rear side of the front axle 25 and bolster devices, together with a cross-section, taken on the perpendicular dotted-line *a*, *a*, of Fig. 2, showing the upper and lower circles of the fifth-wheel and the fore ends of the perch-irons, and all illustrating, 30 (as far as they go,) the important features of my invention herein; Fig. 2, a sectional elevation taken on the perpendicular dotted-line *b*, *b*, of Fig. 1, but including therein the parts of the device that are not shown in 35 Fig. 1 but that are to the rear of said perpendicular dotted-line *a*, *a*, of this view (Fig. 2); Fig. 3, a detail cross-section showing the head-block and the fore end of one of the upper perch-irons or braces, to illustrate the 40 manner in which said perch-iron or brace is constructed and attached to said head-block; Fig. 4, a detail plan view of the head-block rest or plate, showing it apart from the remainder of the device herein; Fig. 5, a sectional view of the axle, axle-bed, one end of 45 the lower-circle and an elevation of the integral clip jaws or arms depending from said lower-circle and illustrating the manner in which said end of the lower-circle is secured 50 in place to said axle and axle-bed; and Fig. 55 6, a fragmentary plan view showing the central portion of the upper-circle and the manner in which it is connected with the reaches of the device herein.

1 indicates the fore or front axle; 2 the axle-bed; 3 the head-block or bolster; 4, 4

the reaches having the upwardly-curved metallic extensions or perch-irons 5, 5, the latter being preferably provided with vertical lugs 6, for accommodating horizontal bolts 7 that 60 connect the reaches to the bolster 3; 8 the head-block plate or rest having a central rearwardly-extending eye 9 that is of much greater thickness than that of the body portion of the head-block plate; 10, 10 the vertical inverted U-shaped clips having lower screw-bolt extensions 11 that engage holes or perforations 11^a in the lateral extensions of the head-block plate and receive securing-nuts 12; 13 the upper-circle connected at its 70 opposite ends to the head-block or bolster 3 by means of vertical bolts 14 whose heads engage countersunk openings made in the under face of the said upper-circle and whose shanks pass upward from the upper-circle 75 through the head-block plate and the bolster for screw-threaded engagement with nuts 15; 16 the lower-circle having integral vertical clip-arms 17, the latter engaging over the axle-bed 2 and the axle 1 and having 80 lower screw-bolt extensions 18 that pass through openings 19 for engagement with nuts 20 to secure said lower-circle firmly in place on the axle-bed; and 21 central lugs 85 projecting horizontally, forwardly and rearwardly from the upper-circle for coupling-engagement with a removable tie-bar 22, vertical bolts 23 being used to connect said lugs 21 with said tie-bar 22, the latter having 90 a transverse semi-circular concavity for receiving and permitting the circular-motion of the lower-circle therein.

The fore ends of the perch-irons or braces 5 are provided with downwardly-projecting pins 24 that engage perforations 25 made in 95 the rearwardly-extending central portion of the head-block plate or rest 8, as best seen in Fig. 3. This peculiar connection of said perch-irons with the head-block plate is very simple and easily made in assembling the 100 parts, and is very firm and secure to prevent lateral and thrust movements.

26, (taken as a whole,) indicates the vertical king-bolt having a shouldered enlarged portion 27 from which projects a screw-threaded upper extension 28 and a downward extension 29, the lower end of which latter is also screw-threaded for the engagement of the nuts 30 and 31. The threaded upper-extension 28 passes through the thickened eye 9 of the head-block plate 8 for engagement by a nut 32. The lower extension

29 passes downward through an eye 33 projecting rearwardly from a clip 34, the latter having a single screw-bolt extension 35 at its fore side that passes through an opening 36 made in a clip-tie 37 and is engaged by a nut 38. The clip-tie 37 passes rearwardly beneath and engages the axle 1 and is provided with a rearwardly-projecting eye 39, through which latter the downwardly-projecting shank 29 of the king-bolt passes for engagement by the securing-nut 30.

A lower perch-iron or brace 40 projects in a curved line forwardly from the underside of the reaches 4, 4 such lower perch-iron spreading out rearwardly in fork-like form, as customary, and having an eye 41 at its fore end through which the lower screw-threaded end of the king-bolt passes for engagement with the fastening-nut 31.

20 In the assembling of the parts they are readily drawn together in compact position by means of a simple form of shouldered king-bolt and the series of vertically-aligned eyes that project rearwardly from the fore-axle and head-block, all as best seen in Fig. 2. The clip 34 with its eye 33 and the clip-tie 37 with its eye 39 makes a very simple form of device through which the lower reduced end of the king-bolt passes and is connected with the axle-bed and fore-axle. The head-block plate with its king-bolt eye 9 and forwardly-projecting lugs or clip-extensions provide a very simple and effective form of device for supporting the king-bolt at its 30 upper reduced end and permitting swiveling of the fore-axle on the head-block and the upper-circle.

25 The provision of the vertical lugs 6 at the fore-ends of the perch-irons 5 is a very simple and effective form of device for use in connection with the horizontal bolts 7 that unite the fore ends of the reaches 4 with the head-block or bolster 3, easily connected and disconnected.

40 The provision of the integral pendent clip-arms 17 at the opposite ends of the

lower-circle 16 is a very simple and effective form of device for use in connection with the lower-clip-ties 19 to connect the said lower-circle with the axle-bed and fore-axle.

50 It will be observed that neither of the two circles of the device has any brace or cross-bar in its structure and that the upper-circle is readily and effectually connected to the reaches by means of integral lugs 42 that project rearwardly therefrom and are connected to the reaches 4, 4, by means of vertical bolts 43, the latter serving to simultaneously connect the rear forks of the lower perch-iron or brace 40 to the reaches.

55 The central sliding-connection 21, 22 and 23 for the upper and lower circles is a simple and effective one and very easily made and released.

60 I claim:

In a vehicle fifth-wheel structure, the combination of a fore-axle, a bolster, a bottom-plate having a pierced rear-extension and secured to the bolster, a pair of perch-irons each having at its fore-end an upright perforated attaching-lug and a pendent pin, the latter adapted to engage an opening in said pierced rear-extension of said bottom-plate, a removable king-bolt provided with an intermediate shouldered-enlargement and with 70 its upper threaded-end adapted for engagement with a central opening in said pierced rear-extension of the bottom-plate, spaced clips on the axle having lower clip-ties, a central clip on the axle carrying an integral 75 rearwardly-extending eye that vertically aligns with the central opening of the rear-extension of the said bottom-plate and is adapted for engagement with the lower shoulder of said king-bolt enlargement, an 80 upper-circle, and a lower-circle, with both circles respectively connected to said bolster and fore-axle.

85 WILLIAM KNAPP.
